(57) **CLAIM**

The ornamental design for a transformer box for use with track lighting, as shown and described.

DESCRIPTION

FIG. 1 is a front elevation view of a transformer box for use with track lighting showing my new design;

FIG. 2 is a top and right side perspective view thereof;

FIG. 3 is a rear and right side perspective view thereof; and,

FIG. 4 is a bottom and left side perspective view thereof. The broken line showing the environment is for illustrative purposes only and forms no part of the claimed design.
